(57) **CLAIM**

An ornamental design for the fluid layering device for centrifugal tube as shown and described.

DESCRIPTION

FIG. 1 is a front elevational view of a fluid layering device for centrifugal tube consisting of an upper cylindrical tube and a detachable lower tube.

FIG. 2 is a right side view of the fluid layering device for centrifugal tube consisting of the upper cylindrical tube and the detachable lower tube (the left side view being a mirror image of the right side view).

FIG. 3 is a rear view of the fluid layering device for centrifugal tube consisting of the upper cylindrical tube and the detachable lower tube.

FIG. 4 is an upper perspective view of the upper cylindrical tube detached from the lower tube.

FIG. 5 is a top view of the fluid layering device for centrifugal tube consisting of the upper cylindrical tube and the detachable lower tube.

FIG. 6 is a bottom view of the upper cylindrical tube of the fluid layering device for centrifugal tube.

FIG. 7 is an upper perspective view of the lower cylindrical tube detached from the upper tube.

FIG. 8 is a top view of the lower cylindrical tube detached from the upper tube; and,

FIG. 9 is a bottom view of the lower cylindrical tube detached from the upper tube.

The broken lines in the drawings illustrate portions of the fluid layering device for centrifugal tube which form no part of the claimed design. The broken lines show edges of the design that form no part of the claimed design.

The symbolic brackets in the Figures indicate the detachment between the upper and lower cylindrical tubes.
